UNITED STATES PATENT OFFICE.

ISAAC O. DAY, OF OTTUMWA, IOWA.

PUMP.

SPECIFICATION forming part of Letters Patent No. 782,493, dated February 14, 1905.

Application filed August 17, 1901. Serial No. 72,340.

To all whom it may concern:

Be it known that I, ISAAC O. DAY, a citizen of the United States, residing at Ottumwa, in the county of Wapello and State of Iowa, have 5 invented a new and useful Pump, of which the following is a specification.

This invention relates generally to pumps, and has for its object to provide a simple and efficient means whereby the water can escape 10 from the pump-barrel, and thereby avoid freezing within the barrel.

With this object in view the invention consists in the peculiar construction of the various parts and in their novel combination and arrangement, all of which will be fully described 15 hereinafter and pointed out in the claims.

In the drawings forming part of this specification, Figure 1 is a sectional view of the pump constructed in accordance with my invention. Fig. 2 is an enlarged sectional view 20 of the check-valve mechanism. Fig. 3 is a horizontal sectional view taken through the plunger-rod above the connecting-pin. Fig. 4 is a detail perspective view of the float, and Fig. 5 is a detail perspective view showing the 25 end of the plunger-rod.

This invention is particularly adapted for use in connection with driven wells.

Referring to the drawings, A indicates the 30 pipe, which is driven into the earth. The pump-barrel B is connected at its upper end to a collar C, which is secured to the platform D, and the head of the pump E is also connected to this collar C. The pump-barrel has 35 a cylinder F suspended therein, the said cylinder being slotted at its lower end, as shown at F', and working through this cylinder is the reciprocating plunger-rod G, carrying the plunger or piston H at its lower end, having 40 the usual valves H'. The lower end of the pump-barrel is closed by means of a casting I, said casting having a central opening K, which is surrounded by a depending collar L, threaded internally and into which the pipe A screws. 45 Upon the inner face of the casting and surrounding the central opening K is an externally-threaded collar M, forming a valve-seat upon which screws the cage N. The casting has an upwardly-projecting internally-

threaded flange I', by means of which the 50 casting is connected to the lower end of the barrel B. The valve O has a depending tubular portion O', which extends down into the circular opening K, said valve resting upon a washer O'', which rests upon the top of the 55 collar M. The valve O rises and falls in the cage N, and, if desired, a nut O''' may be screwed upon the depending portion of the valve. A minute opening is formed in the valve O, through which the water may slowly drain 60 back below the valve. A ball-valve P is swiveled upon the end of a rod Q, which is connected at its upper end to a pin R, said pin passing through the depending lugs S', arranged upon the under side of an annular float 65 S, which works freely upon the lower end of the plunger-rod G, said plunger-rod being slotted longitudinally, as shown at G', to permit the pin R to pass therethrough, so that the float can rise and fall upon the plunger-rod. 70 When the float S is in its lowermost position, as shown in Fig. 1, the slots G' are entirely covered, the float S fitting the plunger-rod G snugly, so that air is not admitted to or through the slots G'. The lower end of the cylinder 75 F is slotted, as shown at F', so that when the float S rises to its highest position it does not close the lower end of the cylinder, so as to prevent admission of water to the said cylinder.

In operation the plunger-rod is reciprocated 80 by means of the ordinary handle or lever, and the water will pass upwardly through the pipe A, lifting the valve O and passing up through cage N. The check-valve P is of course elevated at this moment. Upon the descent of 85 the plunger-rod a portion of the water will be forced past the plunger H and will be elevated at the next stroke of the handle. When the operation of the pump has ceased, a portion of the water contained within the barrel 90 will slowly escape past the plunger H and into the pipe A through the opening in the valve, thus permitting the float to slowly descend until the ball P covers and closes said opening, when the escape of water will be 95 checked. The amount of water remaining above the valve will be regulated by the length of the rod Q and should be sufficient to cover

the plunger or piston H, which is at all times immersed.

It will thus be seen that I provide a simple and efficient means for regulating the escape of 5 the surplus water from the barrel of the pump.

Having thus fully described my invention, what I claim as new, and desire to secure by Letters Patent, is—

- 10 1. The combination with a pump - barrel having a valve-seat at its lower end, a valve adapted to coact with said seat, said valve being perforated, a vertically - slotted plunger, a float movable on the plunger-rod and adapted to close the slot when the float is in its lowest 15 position, a rod carried by the float, and a ball carried by the rod last mentioned and adapted to close the perforation in the valve.
- 20 2. In a pump, the combination with a barrel having a valve-seat at its lower end, of a valve having a seat formed thereon, a plunger-rod carrying a piston, a float movable upon the plunger-rod, and a ball suspended from the said float and adapted to coact with the seat formed on the valve.
- 25 3. In a pump, the combination of a barrel having a valve-seat at its lower end and a cage protecting said valve-seat, a valve working in the cage and having a minute opening therein, of a plunger-rod carrying a piston at its lower end and working in the said barrel, an annular float movable upon the said plunger-rod, a rod depending from the said float, a ball - valve carried by the lower end of said depending rod and adapted to pass through

the cage and close the opening in the valve, 35 substantially as shown and described.

4. In a pump, the combination with the barrel, of a reciprocating plunger therein, a valve below and a float above the plunger, and means for connecting the valve with the float in such 40 manner that the valve will be seated before the escape of all the water above the plunger when the pump is not in use, substantially as described.

5. In a pump, the combination with the barrel, of a reciprocating plunger and a float therein below the frost-line, the float being above the plunger, a valve below the plunger and connected with the float as to be seated before all the water above the plunger escapes when 50 the pump is not in use, substantially as described.

6. In a pump, the combination with the barrel of a reciprocating plunger-rod therein, the lower portion of which is hollow and slotted, a 55 plunger on the end of the rod and a float loosely mounted on the rod at the slotted portion, a pin through the slots and in engagement with the float, a rod connected with the pin and extending below the plunger through 60 the hollow of the plunger - rod, and a valve loosely secured to the lower end of said second-mentioned rod, substantially as described.

ISAAC O. DAY.
